Des. 135,578

PLASTIC BONDING STRIP FOR FABRIC COVERED STRUCTURES

Filed Dec. 31, 1942

INVENTOR:

Charles F. Marschner
by Courtlandt Scovely

HIS ATTORNEY

UNITED STATES PATENT OFFICE

135,578

DESIGN FOR A PLASTIC BONDING STRIP FOR FABRIC COVERED STRUCTURES

Charles F. Marschner, St. Louis, Mo., assignor to
McDonnell Aircraft Corporation, St. Louis, Mo.,
a corporation of Maryland

Application December 31, 1942, Serial No. 109,169

Term of patent 14 years

To all whom it may concern:

Be it known that I, Charles F. Marschner, a citizen of the United States and a resident of the city of St. Louis and State of Missouri, have invented a new, original, and ornamental Design for a Plastic Bonding Strip for Fabric Covered Structures, of which the following is a specification, reference being had to the accompanying drawing, forming part thereof.

Fig. 1 is a top perspective view of a plastic bonding strip for fabric covered structures, showing my new design; and

Fig. 2 is a bottom perspective view of said plastic bonding strip.

I claim:

The ornamental design for a plastic bonding strip for fabric covered structures, as shown.

CHARLES F. MARSCHNER.
